UNITED STATES PATENT OFFICE.

STEPHEN ERNEST MEYER, OF HAYDEN, ARIZONA.

FLOTATION MACHINE.

Application filed April 29, 1927. Serial No. 185,200.

The present invention relates to flotation machines and has for its prime object to provide improvements upon the apparatus shown in Letters Patent No. 1,597,368, issued to me on August 24, 1926.

Another very important object of this invention resides in the improvement of the means of aeration to raise the pulp or feed through froth-forming screens.

With the above and numerous other objects in view as will appear as the description proceeds, the invention resides in certain novel details of construction, and in the combination and arrangement of parts as will be hereinafter more fully described and claimed.

In the drawings:—

Figure 1 is a side-elevation of the flotation machine embodying the features of my invention,

Figure 2 is a top plan view thereof,

Figure 3 is a vertical longitudinal section therethrough,

Figure 4 is a vertical transverse section therethrough.

Referring to the drawing in detail, it will be seen that I provide a casing including the bottom 5, sides 6, and ends 7 and 8. A partition 9 forms with the end 7 an entrance 10 for the feed or pulp. A partition 11 forms with the end 8 an exit 12. Longitudinally extending walls 14 are disposed between partitions 9 and 11 for forming the aerator space therebetween. The aerator is supported on legs 16 rising from the bottom 5. The numeral 20 denotes the main air header which has air supply pipes 25 rising therefrom. A closed casing 24 forms the aerator and has a plurality of slots 38 in the lower portion thereof. A screen 36 extends across the upper edges of the walls 14 and the casing 24 extends through openings therein. Pipes 17 extend upwardly from the bottom of the casing 24 through the top thereof and have caps 17' closing the upper ends of these pipes 17. The pipes 25 extend up through the bottom of the casing 24 and terminate interiorly of the pipe 17 adjacent the top of the casing 24. Walls 33 extend between partitions 9 and 11 in parallel spaced relation being spaced farther apart than walls 14 and being disposed above walls 14 as clearly shown in Figure 4. These walls 33 form froth-retarders. An overflow gate 35 is mounted in guides 2 on the side walls 6 between end wall 8 and partition 11. This gate may be adjusted vertically to properly adjust the pulp or feed level in the machine. The numerals 38' denote the slots in the lower ends of the pipes 17. The numeral 40 denotes the control valve in the air header. An outlet 43 is provided in the lower portion of the end wall 8 for the tailings from the machine. The usual launder troughs 44 are provided on the outside of the side walls 6 and said side walls 6 are provided with openings 45 leading into the launder troughs 44.

The feed or pulp enters at 10 flowing underneath partition 9 where it comes in contact with the air coming from the bottom of pipes 17. It is then drawn up into the aerator space between walls 14 where it is subjected to an intense emulsification. The air, with particles of pulp, is then forced through ports in aerator 24. The air, rising up through the feed or pulp strikes the froth-forming screen 36. The downwardly projecting edges or walls 14 force the air and pulp through the screen thereby forming a froth. The froth is retarded by froth-retarders 33. The retarders 33 are utilized to retard the too rapid discharge of the froth. The air is controlled by control valve 40 on the main air header 20. The air flows from the main air header 20 into the air supply lines 25. The air rises inside these lines 25 which are disposed in pipes 17, to a height above the pulp or feed level. There the air discharges into the larger pipes 17. These pipes 17 are capped at their upper ends as is indicated at 17' so as to force the air back down around the pipes 25 and discharge into the feed through slots 38' in pipes 17. As will be readily understood, this overcomes any feed or pulp running back into air header 20. If the air should stop flowing due to some interruption in operation, the feed or pulp can not flow back into the air header. The gate 35 is used to keep the pulp level in the machine. The feed flows under partition 11 and rising up flows over the top of the gate 35. Particular attention is directed to the novel manner in which I use the two pipes 25 and 17, one inside the other to put the air into the aerator. Due to excess lime in some pulp, it is hard to keep a pipe blowing directly into the pulp open. This apparatus eliminates this trouble to a great extent and is very practical and efficient in actual operation.

It is thought that the construction, utility,

and the advantages of this invention will now be quite apparent to those skilled in this art without a more detailed description thereof. The present embodiment of the invention has been disclosed in detail merely by way of example since in actual practice it attains the features of advantage enumerated as desirable in the statement of the invention and the above description. It will 10 be apparent that changes in the details of construction, and in the combination and arrangement of parts may be resorted to without departing from the spirit or scope of the invention as hereinafter claimed or 15 sacrificing any of its advantages.

Having thus described my invention, what I claim as new is:—

1. In a flotation machine of the class described, a casing having an entrance and an 20 exit for material, aerating means in the casing, said aerating means comprising an elongated hollow structure disposed vertically in the casing and having a pipe extending through the top thereof and the upper end 25 of the pipe being closed, an air header, a second pipe extending through the bottom of the hollow structure into the first pipe, said second pipe connected with said air header, said hollow structure having open- 30 ings in the bottom portion of its side walls,

a screen supported horizontally on and exteriorly of the aerating means, and retarders depending from the side edges of the screen one to each side of the aerating means for forming compartments. 35

2. In a flotation machine of the class described, a casing having an entrance and an exit for material, aerating means in the casing, said aerating means comprising an elongated hollow structure disposed vertically 40 in the casing and having a pipe extending through the top thereof and the upper end of the pipe being closed, an air header, a second pipe extending through the bottom of the hollow structure into the first pipe, said 45 second pipe connected with said air header, said hollow structure having openings in the bottom portion of its side walls, a screen supported horizontally on and exteriorly 50 of the aerating means, retarders depending from the side edges of the screen one to each side of the aerating means for forming compartments, and other retarders extending longitudinally of the casing above the aerating means one to each side thereof in parallelism with the first mentioned retarders and spaced farther apart than the first mentioned retarders. 55

In testimony whereof I affix my signature.

STEPHEN ERNEST MEYER.
